195,976

CHRISTMAS TREE ORNAMENT OR SIMILAR ARTICLE

Arnold Janowitz, New York, N.Y., assignor to Allied
Display Materials, Inc., New York, N.Y.

Filed July 20, 1962, Ser. No. 70,993

Term of patent 7 years

(Cl. D29—1)

FIG. 1

FIG. 3

FIG. 1 is a top plan view of a Christmas tree ornament showing my new design;

FIG. 2 is a front elevational view thereof; and
FIG. 3 is a side elevational view thereof.

I claim:

The ornamental design for a Christmas tree ornament or similar article, as shown.
